CLAIM

The ornamental design for an illuminable display case, substantially as shown and described.

DESCRIPTION

FIG. 1 is a perspective view of an illuminable display case showing my new design;

FIG. 2 is a front elevational view, the rear view being a mirror image thereof;

FIG. 3 is a top plan view;

FIG. 4 is a right side elevational view;

FIG. 5 is a left side elevational view; and

FIG. 6 is a bottom plan view.
